UNITED STATES PATENT OFFICE.

HENRY B. INGLIS, OF DAYTON, OHIO.

GUN REEL FEED UNIT.

Application filed April 18, 1922. Serial No. 555,195.

To all whom it may concern:

Be it known that I, HENRY B. INGLIS, a citizen of the United States, residing at Dayton, in the county of Montgomery and State of Ohio, have invented certain new and useful Improvements in Gun Reel Feed Units, of which the following is a specification.

This invention relates to gun reel feed units for use in conjunction with flexible or fixed gun mounts for aircraft.

The object of the invention is to enable a Browning gun or any belt fed gun to be mounted or handled as a unit, the reel upon which the ammunition belt is wound being removable from and replaceable in a housing or holder attached to the gun. In connection with the reel a feed chute or guide of special novel formation is used to guide the ammunition to the feed way of the gun.

Another object of the invention is to provide a novel mounting for the gun and reel feed unit which will afford a better balance and recoil action of the gun on its horizontal axis and which will also enable the gun to be quickly removed and replaced. The construction further enables a greater amount of ammunition to be carried on the reel, and to be fed to the gun without any increase in width over the gun and reel, at the same time offering the least obstruction to vision in aiming the gun. Furthermore the unit is adaptable to any mounting other than a turret.

To the above end the invention consists in the novel construction, combination and arrangement herein described, illustrated and claimed.

In the accompanying drawings:

Figure 1 is a side elevation of the gun reel feed unit applied to a gun;

Figure 2 is an end view of the same;

Figure 3 is a side elevation of the gun reel feed unit as used in conjunction with a floor mount; and

Figure 4 is a plan view thereof.

The improved gun reel feed unit comprises as one of the main features thereof a gun-supporting or carrying saddle 1, shown as consisting of side plates 2 in spaced parallel relation to each other and connected by suitable cross bracing members.

The side plates 2 at one end are formed with trunnion sockets 3, open at the end to receive the trunnions 4 of the gun 5. At

the opposite end, the side plates 2 are formed with upwardly opening sockets 6 to receive pins 7 carried by the stirrups 8 of the gun 5. By reason of such arrangement the gun 5 may be detached from the saddle 1 by a compound movement of the gun consisting in slightly lifting one end of the gun and then moving the gun lengthwise. The gun is replaced in the same manner.

The saddle 1 in Fig. 1 is connected by the trunnions 9 to the fork arms 10 of a mounting stem 11 which enable the gun 5 to be swung on a horizontal axis. The stem 11 is itself journaled in a socket, for example in the bow of a scarf ring, thereby providing for the swinging of the gun about a vertical axis.

Mounted fast on one side of the saddle 1 is a receptacle, housing or box-like holder 12 for an ammunition reel 13. The journals 14 of said reel fit into bearing slots or notches 15 in the side walls of the holder 12 and are held therein by retaining catches or latches 16 mounted on pivots 17 on the holder and pressed into engagement with the journals 14 by springs 18.

A feed chute extends from a discharge outlet of the holder 12 and, as shown, is composed of channeled guides 19 spaced uniformly from each other with the channels 20 thereof facing each other to guide the side edges and ends of the ammunition. The feed chute is given a quarter twist so as to turn the shells through an arc of ninety degrees and enable them to pass laterally into the feedway of the gun. Thus the reel holder and the feed chute are fixed in relation to the saddle, and the gun and the reel are quickly removable and replaceable.

Under the mounting arrangement shown in Fig. 3, the saddle 1 has extensions 21 formed with arcuate slots 22 to receive a limiting stop 23 such as a bolt carried by a gimbal ring 27. The trunnions 25 of the saddle are mounted in the ring 24 and the latter is mounted by trunnions 26 in another gimbal ring 27. Ring 27 is secured by fastening means 28 to the skin, sheathing or armor plate 29 of the floor of the fuselage of an aircraft, an opening therein being left for orientation of the gun. The gun may thus be swung to any required angular position without disturbing the proper relative attitude of the reel feed mechanism thereto.

A reel-retarding friction brake or shoe

30 adjustable by a milled head 31 prevents the reel from turning faster than the feeding movement of the ammunition belt.

What I claim is:

- 5 1. In a flexible gun mount, a swiveled support, a gun-carrying saddle mounted on trunnions on said support to swing at an angle to axis of movement of the swiveled support, said saddle having sockets to receive the trunnions of the gun, and a gun having its trunnions removably held in said sockets.
- 10 2. In a flexible gun mount, a swiveled support, a gun-carrying saddle mounted on trunnions on said support to swing at an angle to axis of movement of the swiveled support, said saddle having sockets to receive the trunnions of the gun, and a gun having its trunnions removably held in said
- 15 3. In a flexible gun mount, a swiveled support, a gun-carrying saddle mounted on trunnions on said support to swing at an angle to axis of movement of the swiveled support, said saddle having sockets to receive the trunnions of the gun, and an ammunition reel carried by said saddle, the longitudinal axis of said reel being substantially parallel to the longitudinal axis of said gun
- 20 4. In a flexible gun mount, a swiveled support, a gun-carrying saddle mounted on trunnions on said support to swing at an angle to axis of movement of the swiveled support, said saddle having sockets to receive the trunnions of the gun, and a gun having its trunnions removably held in said
- 25 5. In a flexible gun mount, a swiveled support, a gun-carrying saddle mounted on trunnions on said support to swing at an angle to axis of movement of the swiveled support, said saddle having sockets to receive the trunnions of the gun, and a gun having its trunnions removably held in said
- 30 6. In a flexible gun mount, a swiveled support, a gun-carrying saddle mounted on trunnions on said support to swing at an angle to axis of movement of the swiveled support, said saddle having sockets to receive the trunnions of the gun, and an ammunition reel carried by said saddle, the longitudinal axis of said reel being substantially parallel to the longitudinal axis of said gun

trunnions on said support to swing at an 35 angle to axis of movement of the swiveled support, said saddle having sockets to receive trunnions of the gun, an ammunition reel carried by said saddle, the longitudinal axis of said reel being substantially parallel to the longitudinal axis of said gun mount, and quick release means for detaching said reel from the saddle.

5. In a flexible gun mount, a swiveled support, a gun-carrying saddle mounted on trunnions on said support to swing at an angle to axis of movement of the swiveled support, said saddle having sockets to receive the trunnions of the gun, an ammunition reel carried by said saddle with its sides 40 parallel to the axis of the gun, and a feed chute leading from said reel to the feed-way of the gun.

6. In a flexible gun mount, a swiveled support, a gun-carrying saddle mounted on trunnions on said support to swing at an angle to axis of movement of the swiveled support, said saddle having sockets to receive the trunnions of the gun, an ammunition reel carried by said saddle with its sides 45 parallel to the axis of the gun, and a feed chute leading from said reel to the feed-way of the gun, said feed chute being given 50 a quarter twist between its receiving and delivering ends.

In testimony whereof I affix my signature.

HENRY B. INGLIS.
